UNITED STATES PATENT OFFICE.

GEORGE W. HAMMERS, OF BILLINGS, MONTANA.

PLOW.

1,081,961.

Specification of Letters Patent.

Patented Dec. 23, 1913.

Application filed October 29, 1912. Serial No. 728,478.

To all whom it may concern:

Be it known that I, GEORGE W. HAMMERS, a citizen of the United States, residing at Billings, in the county of Yellowstone and 5 State of Montana, have invented a new and useful Plow, of which the following is a specification.

One object of the present invention, therefore, is to provide means whereby a colter 10 may be assembled readily and quickly with the landside of a plow share.

Another object of the invention is to provide a structure whereby a colter will be held securely and closely in abutment with 15 the landside.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, can be made within the scope of what is claimed, with 25 out departing from the spirit of the invention.

In the drawings:—Figure 1 shows the invention in perspective, parts being broken away; Fig. 2 is a longitudinal section of 30 the landside, the view showing the colter applied to and held upon the landside. Fig. 3 is a transverse section through the landside and through the colter; and Fig. 4 is a side elevation of the colter.

35 In the drawings, the numeral 1 indicates the landside and the numeral 2 indicates the share.

The numeral 3 indicates a colter, the same 40 having an extension 4 adapted to lie along the outer face of the landside 1. The body portion of the colter 3 is equipped with a rearwardly and inwardly inclined stud 5 adapted to be received in a rearwardly and 45 inwardly inclined opening 6 which is formed in the landside 1. In the extension 4 of the colter 3 there is an opening 7, alinable with an opening 8 in the landside 1. Through the openings 7 and 8 is passed a retaining member 9 having at its outer end a head 10 adapted to engage the extension 4 of the colter 3. The inner end of the retaining member 9 is provided with a slot 11. Mounted in the slot 11 is a lever 12, taking 50 the form of a wedge bar, the forward end of the lever 12 being fulcrumed, as indicated

at 14, upon the inner face of the landside 1. The lever 12 is equipped in its inner edge with a plurality of notches 16, any one of which may be engaged with the retaining member 9 when the lever 12 is tilted. In 60 order to effect a tilting of the lever 12, a fulcrum pin 17 is passed through the rear end of the lever, the pin 17 supporting a cam 18 adapted to bear against the inner face of the landside 1, the cam 18 terminating in a rearwardly extending operating handle 19.

In practical operation, the stud 5 is inserted into the opening 6 and when the colter 3 is pushed rearwardly, the same will be advanced transversely, so as to bear closely and securely against the outer face of the landside 1. The retaining member 9 is mounted in place and the lever 12 is inserted into the opening 11 in the retaining member 9, one of the notches 16 being engaged with the retaining member. When the handle 19 is manipulated, the cam 18 will bear against the inner face of the landside 1 and tilt lever 12 upon its fulcrum point 14. Thus, the retaining member 9 will be advanced longitudinally and the head 10 of the retaining member will engage and hold in place the colter 3.

From the foregoing it will be seen that a 85 device has been provided whereby a colter may be attached readily to the landside of a plow and, with equal facility, may be removed therefrom. The construction, further, is such that the colter will lie closely 90 against the outer side of the landside.

Having thus described the invention, what is claimed is:—

1. In a plow, a landside having a rearwardly and inwardly inclined opening; a colter having a rearwardly and inwardly inclined stud adapted to register in the opening; a retaining member engaged with the colter and with the landside; and adjustable means upon the retaining member for engaging the inner face of the landside. 95

2. In a plow, a landside having a rearwardly and inwardly inclined opening; a colter having a rearwardly and inwardly inclined stud adapted to register in the opening; a retaining member engaging with the colter and with the landside; a bar inserted through the retaining member; and adjustable means upon one end of the bar for thrusting the other end of the bar against the 100 105 110

inner face of the landside, to impart longitudinal movement to the retaining member.

3. In a plow, a landside; a colter; the landside being provided with a rearwardly and inwardly inclined opening, and the colter being provided with a rearwardly and inwardly inclined stud adapted to register with the opening; a retaining member engaged with the colter and with the landside; a bar inserted through the retaining member and bearing at one end against the inner face of the landside; and a cam upon the other end of the bar, adapted to engage the inner face of the landside.

4. In a plow, a landside, a colter; a retaining member connected with the colter and extended through the landside; a bar extended through the inner end of the retaining member and provided in its edge with a plurality of notches adapted to engage the retaining member; and a cam upon one end of the bar, adapted to engage

the inner face of the landside to swing the other end of the bar against the inner face of the landside to advance the retaining member longitudinally.

5. In a plow, a landside; a colter applied to the landside; a retaining member mounted upon the colter and extended through the landside; a lever pivotally supported intermediate its ends on the retaining member and located upon the opposite side of the landside from the colter; and adjustable means mounted upon one arm of the lever for forcing the other arm of the lever into engagement with the landside.

In testimony that I claim the foregoing as my own, I have hereto affixed my signature in the presence of two witnesses.

GEORGE W. HAMMERS.
